VIBRATING TABLE

Cyril Maurice Grahame Calver, Bushey, England

Application March 14, 1946, Serial No. 654,288
In Great Britain March 15, 1945

11 Claims. (Cl. 74—61)

1

This invention consists in improvements in or relating to vibrating tables which have been particularly designed for testing aircraft instruments under conditions which can be adjusted to simulate very closely the vibration conditions to which those instruments would be subjected when the aircraft carrying them is in flight. Although the invention is primarily designed for this purpose it is to be understood that it is not limited to this use and may be employed for any purpose in which a vibrating table is required to be vibrated in two planes disposed at an angle to one another, e. g. at a right-angle and in which the phase relationship of vibrations can be readily adjusted.

The present invention comprises broadly in combination a vibratory table, a carriage for the table permitting movement of the latter in two planes angularly displaced, at least two rotary shafts having an eccentric coupling to the table with the two shafts disposed with their axes angularly displaced with respect to one another at the required angle and means to adjust the eccentricity of the coupling between each shaft and the table.

One preferred example of the invention will now be described with the aid of the accompanying drawings in which:

Figure 1 is a side elevation showing the vibration table together with the main driving motor.

Figure 2 is a section on the 2—2 of Figure 1.

Figure 3 is a section in a plane at right-angles to that of Figure 2 and containing the axis of the main driving shaft.

Figure 4 is a section of a detail taken on the line 4—4 of Figure 3, and

Figure 5 is a diagrammatic illustration of a portion of the vibratory shaft shown in Figure 2 to illustrate more clearly the eccentricity of the shaft and the several parts associated with it.

Figure 6 is an exploded view of the main parts making up the vibratory table and sub-frame and

Figure 7 is an enlarged sectional detail of the coupling to one of the main vibration shafts and the means for angularly adjusting it.

Like reference numerals indicate like parts in the several figures of the drawings.

The main base 10 upon which the table is supported may be of any preferred form and is conveniently a metal casting in which are provided bearings 11 and 12 for main driving shaft 13. Driving through a coupling 85 this shaft rotates driving shaft 113 to which is splined a bevel gear 14 with which are engaged two other bevel gears

2

15 and 16 mounted respectively on two vibration shafts 17 and 18. One of these vibration shafts, namely the shaft 17, is arranged with its axis at right-angles to and in a plane containing the axis of the main driving shaft 113. This shaft as shown in Figure 5, has ground ends 117 which rotate in the shaft bearings, the centre portion 19 is eccentrically ground to ends 117. This centre portion 19 carries a tightly fitting sleeve 20, the outside of which is also ground eccentric with its own bore and the centre portion 19. The axes for the respective parts 17, 19 and 20 are indicated at 21, 22 and 23 respectively. It is to be understood, however, that eccentricity of the various parts is grossly exaggerated in the illustration in order to show the relationship of these eccentrically designed parts, and in practice, as only comparatively small vibrations are required the degree of eccentricity in all cases will be comparatively slight.

Sleeve 20 is in actual construction, as shown in Figure 2, composed of three portions, 24, 25 and 26 of which the outer portions 24 and 26 are carried in bearings indicated as a whole by reference numerals 27 and 28. These bearings are carried in housings 29 and 30 provided in the bottom of a sub-frame 31 to which vertical vibrations will be imparted when shaft 17 is rotated.

As shown more clearly in Figures 3 and 6, the vibratory table 32 is supported on sub-frame 31 through the medium of a spaced series of balls 33 which are housed in a ring 34 so that vertical motion is transmitted from the sub-frame to the table through balls 33. At the same time these balls provide an anti-friction support for table 32 when it is to partake of vibrations, say in the horizontal plane or in any plane in which a second series of vibrations is intended.

In the example shown, the two sets of vibrations are intended to take place in two planes at right angles to one another, and in consequence the vibration shafts 17 and 18 are disposed with their axes at right angles to one another.

Sub-frame 31, which is mounted by the bearings described on shaft 17, is guided for its vertical movements by means of a plate 131. This plate has tenons 132 arranged vertically one above the other to engage in corresponding grooves in an end bearing standard 100, and on the opposite face has other tenons 133 in line at right angles to tenons 132, and these tenons 133 slide in grooves formed to correspond with them in the wall of sub-frame 31.

A similar plate 134 is interposed between sub-frame 31 and table 32, the latter having grooved

guides 135 to engage tenons 136 on plate 134. The latter also has other tenons 137 which engage in grooved guides 138 in sub-frame 31. Thus, it will be clearly seen that the vibratory table can move independently of the sub-frame in its guides in one direction, and is bodily moved by the sub-frame in a direction at right angles, this latter movement of the sub-frame being permitted and guided by reason of the provision of plate 131.

The three portions 24, 25 and 26 of the sleeve are interengaged by dogs as shown at 35 and are held thus in engagement with one another after assembly by means of thrust bearing 36. The outer end of sleeve portion 24 where it projects from bearing housing 29, is formed as one element of a comparatively finely toothed clutch 37 and this co-operates with a second companion clutch element 38, splined on the left hand end of shaft 17. Thus the clutch element 38 may be moved into and out from engagement with the clutch element 37 in order to lock or free the sleeve 24, 25 and 26 to and from shaft 17 respectively.

When adjusting the amplitude of vibration imparted from shaft 17 relative rotation between the shaft and its sleeve will have to be made and for this adjustment the clutch 37, 38 is actuated by the following means.

Shaft 17 is formed with a screw threaded enlargement 67 and this is engaged by nut 68. In the nut 68 is formed a groove accommodating a split ring 70 which is housed in a recess formed in gear ring 73. The split ring 70 and gear ring 73 are secured to clutch member 38 by means of screws and dowels, holes 72 are drilled in the nut to give access to these screws and dowels. The gear teeth on gear ring 73 are engageable when clutch 37, 38 is disengaged by pinion 74 secured to and rotatable with shaft 75. The shaft 75 is slidable in bearing 76 and is normally spring urged outwardly by means of spring 77 compressed between the end of bearing 76 and the interior face of a cap 78 which is screw-threaded on to shaft 75 and is secured thereon by means of a lock nut 79.

A sleeve 84 with clutch teeth machined on one end is secured to shaft 75 by means of a pin 80 and is engageable by a similar sleeve 81 with clutch teeth formed thereon. The sleeve 81 is secured to crank handle 82.

Thus when the clutch 37, 38 has been disengaged as shown in Figure 2, crank handle 82 can be applied to shaft 75 and the whole moved inwardly against spring 79 until pinion 74 meshes with gear ring 73. Rotation of crank handle 72 will then rotate shaft 17 because clutch member 38 is splined as at 83 to shaft 17.

After the shaft has been adjusted to its required angular position crank handle 82 is removed, spring 77 moves shaft 75 to withdraw pinion 74 from engagement with gear ring 73 and thereafter by turning nut 68 the clutch part 38 will be moved back into engagement with clutch part 37. As nut 68 can rotate freely with respect to ring 70, the clutch part 38 will not be rotated when nut 68 is rotated, and rotational movement of the latter, by engagement with thread 67 will, according to direction of rotation, move the clutch member in one direction or the other. The outer surface of nut 68 is formed to be readily engageable by a tool by which it can be rotated when desired.

One of the clutch elements 37, 38 is marked on the outside with a scale to which a setting mark on the companion element can be adjusted in 78

order to regulate and ascertain the angular movement of the sleeve relatively to the shaft for the purpose of adjusting the throw which will be imparted vertically to the sub-frame 31 as shaft 17 is rotated. Thus adjustment is, of course, obtained by altering the angular relationship of the eccentric portions of the shaft and sleeve.

A second and similar vibratory shaft 18 (Figure 3) and similar adjusting devices therefor are provided. As in the main, the shaft 18 and its sleeve 44 will be similar to the shaft 17 and its sleeve, no detailed description of this second vibratory shaft construction is thought to be necessary but it should be stated that in this case the two clutch elements corresponding to 37, and 38 are indicated at 40 and 41. Lock nuts 42 and 43 are provided to hold the clutch parts 40 and 41 in engagement after they have been sent relatively to one another to produce the relative angular adjustment required between the eccentric portions of shaft 18 and its surrounding eccentric sleeve 44.

After clutch parts 40 and 41 have been separated a tool 140 can be applied to clutch part 41 in order to turn shaft 18 within its sleeve in a similar manner to and for the same purpose as that for which shaft 17 is angularly adjustable relatively to its sleeve after clutch 37, 38 has been disconnected.

Sleeve 44 is received in anti-friction bearing 45 carried by table 32 so that horizontal vibrations are imparted directly to the table. Thus the latter can be subjected to vertical vibrations from shaft 17 and horizontal vibrations from shaft 18 and the amplitude of the vibrations derived from the rotation of both these shafts is capable of adjustment in very fine degrees from zero to whatever maximum is imposed by the degree of an eccentricity of the shafts and sleeves.

When it is necessary to adjust the phase angle of the vibrations imparted to table 32 from vibratory shafts 17 and 18, it is necessary to rotate one or the other or both of these shafts in company with its sleeve without disturbing the angular adjustment between that shaft and its sleeve. For this purpose it is necessary first to free the main driving bevel gear 14 from driving engagement with bevel gears 15 and 16.

In order to enable this disconnection to be effected the driving shaft is in two parts 13 and 113. One part 13 is mounted in bearings 11 and 12 and the other, 113 is mounted in bearings 47 carried in housing 48 which is itself carried in a bracket 49 at the base of sub-frame 31, so as to be movable axially.

The driving power is transmitted from the driving shaft 13 to the other 113 by means of a universal coupling 85, one half of which is secured by splines to 13. The other half 113 is splined to the coupling but not secured, allowing driving shaft 113 to be axially movable therein when moving the housing 48 which carries the shaft 113 and the bevel gear 14 which is splined to it, into the disengaged position.

The main bevel gear 14 is disengaged by means of a hand wheel 55 secured by a pin to a screw 53. The screw is mounted in a bearing 54 secured to the side of sub-frame 31, any unintentional axial movement of screw 53 being eliminated by adjusting two locknuts 58. As the handwheel 55 and screw 53 rotate in one direction, the screw operates the rack 52 which is carried in a guide 51 formed in the top of the bracket 49. The rack meshes with the teeth 50 formed on the housing 48 and rotates the housing. This

rotational movement is converted into an axial movement by co-operation of the helical slot 56, formed in housing 48, and an actuating pin 57. This actuating pin is secured by means of a thread and pin 87 to the base of bracket 49. Thus shaft 113 is moved endwise so as to carry the main bevel gear 14 out of engagement with pinions 15 and 16 when it is desired to adjust the phase angle.

The main bevel gear 14 is engaged by rotating the handwheel 55 in the opposite direction to that described for disengagement so operating the screw 53 and rack 52 and rotating the housing 48 which moves axially, owing to the helical slot 56 and the actuating pin, back to engaged position. When engaged position is reached the housing is held by the rack, which stops rotary movement and is locked between the actuating pin and the locking plate 86; this stops axial movement. The locking plate 86 is secured to the back of the housing 48 by means of screws. Thus shaft 113, is moved back to engaged position carrying main bevel gear 14 to its original position meshing with pinions 15 and 16.

The main drive can be obtained by any preferred prime mover, such as an electric motor 60, as shown in Figure 1. As it is difficult commercially to obtain a motor which can be run at any speed from zero to the high speeds required, it is preferable to employ a motor having a slower maximum speed than that requisite for the maximum vibration speed and to gear this motor by a 2:1 step-up gear or a step-up gear of any other preferred ratio as may be found necessary. The motor shaft 61, as will be seen in Figure 3, is thus geared by step-up gearing 62 to shaft 13.

In the case of certain aircraft instruments it is sometimes necessary that the internal mechanism thereof should be rotated during the vibration test. For this purpose a flexible drive is provided, indicated in Figure 1 at 63 and this flexible shaft is driven by a comparatively small motor (not shown) housed within the base portion of the apparatus. For the sake of illustration, flexible shaft 63 is shown as connected to the driving spindle to one or more of the instruments in an instrument panel 64 shown in the position in which it will be carried between brackets 65 supported on the main table 32. Flexible shaft 63 will preferably be provided at 66 with a nipple or other connector by which it can be readily attached to and detached from the instrument spindle.

It will be understood from the foregoing description that the vibratory table can be subjected simultaneously to vibrations in two different planes and that the eccentric portions of the vibratory shafts in relation to the eccentric sleeves surrounding them can be adjusted to produce vibrations ranging from zero to the desired maximum. Hence vibrations of any magnitude from zero to this maximum can be applied to table 32 in either plane singly or in both planes simultaneously and moreover the phase angle of the two sets of vibrations can be readily and rapidly changed as and when desired in addition to changing the amplitude thereof.

I claim:

1. A vibration test machine comprising in combination a vibratory table, a carriage for the table permitting movement of the latter in two planes angularly displaced, at least two rotary shafts, each having an eccentric coupling to the table, with the two shafts disposed with their axes

angularly displaced with respect to one another at the required angle, and means to adjust the eccentricity of the coupling between each shaft and the table.

- 5 2. A vibration test machine according to claim 1 in which the operative portion of each vibration shaft is formed, as to its outer surface, eccentrically with respect to the axis of rotation of the shaft.
- 10 3. A vibration test machine according to claim 1 in which part of the eccentric coupling between each vibration shaft and the table comprises a sleeve which surrounds the shaft and which has its operative surface formed eccentrically with respect to its through-way axis.
- 15 4. A vibration test machine according to claim 1 in which part of the eccentric coupling between each vibration shaft and the table comprises a sleeve which surrounds the shaft and which has 20 its operative surface formed eccentrically with respect to its through-way axis, and in which each vibration shaft is coupled to its associated sleeve by means of a disconnectable coupling.
- 25 5. A vibration test machine according to claim 1 comprising a main driving shaft, a main driving gear rotated thereby, other gears which mesh with the main driving gear and are coupled respectively to the vibration shafts, and means to 30 connect and disconnect at will the main driving gear from the two driven gears.
- 35 6. A vibration test machine according to claim 1 comprising a main driving shaft, a main driving gear rotated thereby, other gears which mesh with the main driving gear and are coupled respectively to the vibration shafts and means to connect and disconnect at will the main driving gear from the two driven gears, said means comprising a bearing carrying the main driving gear, 40 means for rotatably mounting the bearing in a support, means to rotate the bearing, and a cam device operable on the bearing as it is rotated for moving it axially.
- 45 7. A vibration test machine according to claim 1 comprising a main driving shaft, a main driving gear rotated thereby, other gears which mesh with the main driving gear and are coupled respectively to the vibration shafts, means to connect and disconnect at will the main driving gear 50 from the two driven gears, said means comprising a bearing carrying the main driving gear, means for rotatably mounting the bearing in a support, means to rotate the bearing, and a cam device operable on the bearing as it is rotated for moving it axially, the said means for rotating the bearing comprising a tangentially disposed rack meshing with gear teeth formed on the outer surface of the bearing, and operating means to move the rack endwise to rotate the sleeve.
- 55 8. A vibration test machine according to claim 1 comprising a main driving shaft, a main driving gear rotated thereby, other gears which mesh with the main driving gear and are coupled respectively to the vibration shafts, means to connect and disconnect at will the main driving gear 60 from the two driven gears, said means comprising a bearing carrying the main driving gear, means for rotatably mounting the bearing in a support, means to rotate the bearing, and a cam device operable on the bearing as it is rotated for moving it axially, the said means for rotating the bearing comprising a tangentially disposed rack meshing with gear teeth formed on the outer surface of the bearing, and operating means to move the rack endwise and 65 75 means which serves to move the rack endwise and

comprises a lead screw engaging the rack and rotatable in fixed bearings in the machine.

9. A vibration test machine according to claim 1 comprising a main driving shaft, a main driving gear rotated thereby, other gears which mesh with the main driving gear and are coupled respectively to the vibration shafts and means to connect and disconnect at will the main driving gear from the two driven gears, said means comprising a bearing carrying the main driving gear, means for rotatably mounting the bearing in a support, means to rotate the bearing, and a cam device operable on the bearing as it is rotated for moving it axially, the said cam means comprising a slot and a pin working therein whereof the slot and pin are provided one on the bearing and one on a fixed guide in which the bearing is axially movable.

10. A vibration test machine according to claim 1 in which the operative portion of the sleeve surrounding one of the vibration shafts is received within a bearing in the table itself, and the latter is mounted on a sub-frame over which

it can move under vibrations imparted by the shaft just referred to, and the operative portion of the sleeve of the other vibration shaft is received in a bearing carried by the sub-frame.

5 11. A vibration test machine according to claim 1 in which an auxiliary motor is housed within the machine and a flexible driving shaft connected with the motor is provided for attachment to a rotating part of an instrument to be tested for vibration by the machine.
